CLAIM

The ornamental design for a travel bottle cap having a twisting locking ring body, as shown and described.

DESCRIPTION

FIG. 1 is a top perspective view of a travel bottle cap having a twisting locking ring body showing our new design in a position of use attached to an unclaimed bottle drawn in broken lines,

FIG. 2 is a bottom perspective view of the travel bottle cap having a twisting locking ring body of FIG. 1 shown removed from the unclaimed bottle,

FIG. 3 is a top view thereof,

FIG. 4 is a bottom view thereof,

FIG. 5 is a front view thereof,

FIG. 6 is a rear view thereof,

FIG. 7 is a left side view thereof,

FIG. 8 is a right side view thereof,

FIG. 9 is a top perspective view of the travel bottle cap having a twisting locking ring body of FIG. 1 shown in a closed position and locked configuration; and,

FIG. 10 is a top perspective view thereof in an alternate unlocked configuration.

The broken lines illustrating a bottle depict environment and form no part of the claimed design. All other broken lines depict portions of the travel bottle cap having a twisting locking ring body that form no part of the claimed design.
